UNITED STATES PATENT OFFICE

161,034

HAMMER

Mads Marthinsen, Michigan City, Ind.

Application October 13, 1949, Serial No. 5,472

Term of patent 14 years

(Cl. D93—4)

To all whom it may concern:

Be it known that I, Mads Marthinsen, a citizen of the United States of America, residing at 412 Fir Street, Michigan City, Indiana, have invented a new, original, and ornamental Design for a Hammer, of which the following is a specification, reference being made to the accompanying drawing forming part hereof.

Referring to the drawings, Fig. 1 is a side elevational view (the other side being identical); Fig. 2 is an end elevational view; and Fig. 3 is a top plan view of a hammer embodying my new design.

I claim:

The ornamental design for a hammer, substantially as shown.

MADS MARTHINSEN.
